UNITED STATES PATENT OFFICE

107,724

DESIGN FOR A BOAT HULL

Alfred E. Luders, Stamford, Conn.

Application May 1, 1937, Serial No. 69,116

Term of patent 14 years

To all whom it may concern:

Be it known that I, Alfred E. Luders, a citizen of the United States, residing at Stamford, in the county of Fairfield and State of Connecticut, have invented a new, original, and ornamental Design for a Boat Hull, of which the following is a specification, reference being had to the accompanying drawing, forming a part thereof.

In the drawing, Fig. 1 is a side elevation of a boat hull showing my new design; Fig. 2 is a per-

spective front view of said hull; Fig. 3 is a transverse sectional view indicated by the line 3—3 on Fig. 1; Fig. 4 is a bottom plan of the hull.

The dominant feature of the design is the forward portion of the hull. The top of the boat hull is conventional.

I claim:

The ornamental design for a boat hull, substantially as shown and described.

ALFRED E. LUDERS.
